UNITED STATES PATENT OFFICE.

WILFRID NIELD ROBINSON, OF ROCHDALE, ENGLAND, ASSIGNOR TO THOMAS ROBINSON & SON LIMITED, OF ROCHDALE, ENGLAND, A LIMITED LIABILITY COMPANY OF ENGLAND.

APPARATUS FOR DRYING AND CONDITIONING GRAIN AND SIMILAR GRANULAR SUBSTANCES.

Application filed February 9, 1924. Serial No. 691,709.

To all whom it may concern:

Be it known that I, WILFRID NIELD ROBINSON, a subject of the King of England, and residing at Rochdale, in the county of Lancaster, England, have invented Improvements in or Connected with Apparatus for Drying and Conditioning Grain and Similar Granular Substances, of which the following is a specification.

10 This invention has reference to apparatus or machinery for drying or conditioning grain or similar substances, of the kind in which the grain or material in its fall or flow between upper and lower portions of 15 the apparatus or machine, is caused to pass over internally heated devices, i. e. a series of interconnected vessels, generally called "radiators," which are heated internally by a heating fluid; and the objects and effects 20 of the present invention are to provide improvements in connection with such apparatus or machines, by which the effect as regards the treating or conditioning of the bulk of the material passed through the 25 machine is rendered uniform, and the output or capacity of a given size or cost of apparatus is rendered relatively high; whilst a further object is to provide a construction which is inexpensive, and which is simple, 30 and the time taken for erection or installation is relatively small.

Generally, in apparatus of the kind referred to, it is found that the effect of the treatment on the material is non-uniform, 35 so that the condition of the grain or material delivered is of an uneven condition, some of which being relatively unconditioned, and the other conditioned, and this is obviated by this invention, by rendering 40 it uniform.

In connection with the drying or conditioning apparatus and the mode of treatment hereinafter described, the improvements under this invention are comprised.

45 Between the "radiators," which may consist of a multiplicity of interconnected hollow vessels, sets of which are arranged in parallel in tiers, spaces exist between the more or less flat sides (which are narrowed 50 towards the edges) through which the grain or material passes down in streams, in its treatment.

The apparatus or machine according to

this invention is so constructed or arranged that all the streams of the body of the material (which is divided into a multiplicity of streams) are caused to be acted upon by the hot surfaces of the radiators and heated, to accomplish which, some of the streams or parts of the body of material passing down through the apparatus are controlled by means hereinafter explained, and directed or diverted, so that no parts of the body or streams of the material are acted upon by the heating surfaces of the radiators, some of which otherwise would pass in columns or streams down through the apparatus without coming into contact with, or being properly acted upon by, the heating surfaces. This is prevented in this machine or apparatus, and the flow of the whole body of the material is so controlled, that all parts of it must become, and are, 70 acted upon, and a uniform result of condition and treatment of the material is accomplished.

The controlling or directing or diverting means referred to may consist in providing over the adjacent upper edges of the adjacent parallel sets of the interconnected radiators, plates or angle ridge devices, resting on the top edges of the radiators at each of the adjacent side edges of the sets, so that the grain or material will be controlled and directed in its flow or fall, away from 80 these edge parts of the radiators, towards their centres, and thus are brought into the portion of the surface of same from which a relatively large quantity of heat is being given off or radiated, and which in the adjacent radiators are relatively close together.

Further, in apparatus or machines of the kind referred to, the grain or material to be treated is passed in a plurality of comparatively narrow or thin streams down through conduits at the upper part of the apparatus, and the grain in passing through these conduits is subjected to the direct action of and contact with hot air which passes 95 through it; and this air is of a relatively high temperature, say up to 180° Fahr., and is heated by a heater external to the apparatus, preferably a steam heated air heater, prior to delivery to the "radiator" 100 portion below, and is forced through the 105

streams of material by an air forcing apparatus, preferably a suction fan; and by the employment of relatively hot air, wet grain or like material, or grain or material 5 containing a relatively large percentage of moisture or that requiring to be dried to a very low moisture content, the degree of drying required can be accomplished.

The heating medium supplied to the radiator sections consists of hot water, heated 10 by a water heater or heat interchanger, in which the heat is supplied by steam from a steam generator; and this water is supplied to the various radiator sections at the required temperature, and returned from them 15 to the water heater to receive a further increment of heat, and so is continuously circulated by natural circulation.

Air is also passed through these radiator 20 sections or chambers, and through the material passing down through them, such air being forced through them, and the stream of material falling through them, say by the suction fan above referred to.

At the bottom of the apparatus, a part or 25 section is provided in which the material is cooled by air at atmospheric temperature, and is in the form of narrow conduits, through which relatively thin streams of 30 hot grain or material fall or flow; and while flowing through these conduits the air is caused to pass, or is forced through it, say by the same suction fan above referred to.

The invention is illustrated in the annexed 35 drawings, and it will be further described with reference to them.

In these drawings, Figure 1 is an elevation, showing the complete apparatus diagrammatically.

Figure 2 is a section through one of the radiator sections, showing the improvements 40 connected with these sections of this radiator portion of the apparatus or machine; Figure 3 is an elevation of same, and Figure 4 is a plan.

Figure 5 is a vertical section showing the construction of the upper air heating and drying part.

Generally 1 represents the portion of the 50 apparatus at the top in which the material is treated or dried by direct contact and action of hot air; 2 represents generally the section or portion of the apparatus in which the material is subjected to surface and radiant heat by internally heated "radiators"; and 3 represents the lower section or part 55 in which the hot material from the radiator section is treated by contact with air of atmospheric temperature.

4 is the heater for heating the air for use 60 in the air drying section of the apparatus; 5 is the heater for heating water used in the radiator sections 2; and 6 represents the steam generator for supplying heating steam to the air heater 4, and water heater 5.

7 is the suction fan for forcing air through the streams of grain or material passing down through the conduits in the drying section 1; for forcing atmospheric air through the different sections or parts of the radiator part 2 for absorbing or taking up and carrying off moisture from the hot grain; and for forcing air at atmospheric temperature through the streams of grain falling through the section 3.

The conduits through which the grain or material passes in narrow or thin streams through the hot air treatment in section 1 are marked 10, grain being supplied to the upper parts of same, through hopper shaped mouths, as shown, to which it is distributed in any known suitable way, so that they are supplied with material which will charge them all uniformly. 11 is the general supply hopper of the apparatus.

A form of construction of the conduits 10 is given in Figure 5, in which the walls of the conduit are provided with apertures 12 and internal inclined shelves 13, and the air enters the streams through the apertures at one side, and leaves through those at the other, and it passes from one conduit to another through the chambers 14, which lie between the conduits. This section 1 is divided into an upper or lower portion by a floor or diaphragm 15, so that there are two chambers into which separate supplies of hot air will be supplied by two hot air supply pipes 16.

The air, carrying with it the moisture taken up, is conducted from the upper part 100 of the apparatus, by pipes 17 to a general air main 18, connected to the air intake of the fan 7; and it is conducted away from the chambers or sections of the radiator part 105 2, by conduits or branch pipes 19 connected with the main 18, and air inlets 19* which are on the opposite side to the conduits or pipes 19. Both these inlets 19* and the conduits 19 extend along the whole of the sides 110 of the different sections of the apparatus, and at the lower portions of same, viz, beneath the lower set of radiators of the sections which are supported on the transverse beams marked 47*. Thus this air passes through the stream or streams of material in flowing from the lower set of radiators of each section or chamber, to the next one below.

The cooling section 3 is similarly formed 120 as regards the air supply and form of conduits as that of the hot air portion 1, viz, it is formed of a number of narrow conduits 21 with hopper shaped upper openings, and spaces 22 between them; and the walls of these conduits 21 may be assumed to be of the same construction as those described with reference to Figure 5 in connection with the hot air section 1. The air after 125 passing through the conduits 21 and the 130

streams of material flowing through them, is conducted by pipes 23 to the general rising air main 18; and the dried and cooled grain or material is delivered from the apparatus by the discharge hopper shoot 24.

The whole casing or body of the apparatus or machine may be built up in sections from top to bottom similarly to those shown in Figures 2 to 4.

10 The hot air supplied from the air heater 4 may be raised to a temperature of from zero to 180° Fahr. by steam supplied to it; and this heater may be of tubular or other known kind of gaseous fluid heat inter-
15 changer, the heat being transferred from the walls of the tubes or the like, through which the steam or air is passed, as the case may be, and so transferred to the air.

Similarly the water heater 5 may be of
20 any known suitable type of heat inter-
changer, in which the heat of steam is transferred to water in a closed circulating system.

The radiators are marked 30, and in
25 Figures 2 to 4 their central portions 31 project from their sides (which are flat with curved edges) and these parts 31 in the adjacent radiators abut against one another, and are connected together at this point, 30 preferably above and below by ferrules 32 fitting in the holes 33.

34 are the water supply branches of the tiers or radiators in each section; and 35 are the water discharge branches; while the
35 pipes 36 connect the lower and upper tiers together. 37 and 38 are the pipes to which the branches 34 and 35 are connected, and which are connected to vertical main water supply and discharge pipes 39 and 40 respectively.

40 The directing means connected with the radiators 30 in the case shown, consist of ridge shaped or inclined devices 42, extending across the casing 43, the lower edges of which rest on the upper edges of the adjacent radiators, and therefore direct the columns or streams of grain or material falling down, onto parts of the surface of the radiators which lie in the planes between these edges, and the projections or bosses 31 of the radiators. Normally, and without such controlling or directing means, spaces of considerable area vertically will exist between the edges of each pair of radiators of an interconnected set, and a pair adjacent to them; such space is marked 44 in Figure 4, and the area is indicated by the arrow headed cross lines.

Without these controlling means, the
60 streams of grain will flow at these points 44, from the top of the apparatus to the bottom in columns of considerable cross section, so that the bulk of such columns, or large portions thereof, can pass through the apparatus without being properly heated

and conditioned; and at a greater rate than that passing in streams over other parts of the radiator.

Depending from the distributors or directors 42, are divisions 45 extending from side to side of the apparatus, similarly to the ridge devices 42, which assist in or promote the directing and keeping of the grain in contact with or near the surfaces of the radiators; and a similar device to 45, 70 marked 46, lies between the adjacent edges of the lower tier of a pair beneath the hollow beams 47, which rest on the upper edges of the lower radiators, and support the upper radiators above, and which also direct 75 and prevent the grain from flowing out of contact with the heating parts of the radiators and bring it under the influence of the part of their surfaces away from their edges. 80

Thus, in a line between the top of each section consisting of one, two or more tiers of radiators and their bottom, there are the controlling and directing upper devices 42, 85 the devices 45 below same, the bearers 47 90 which divert the streams from the planes between the radiators, and the plate devices 46.

By the special construction shown a highly advantageous manner of carrying 95 out the invention is provided, by which the objects and effects above referred to are accomplished.

What is claimed is:—

1. Apparatus for drying or conditioning 100 grain or similar substances, comprising an upper part adapted to cause the material to pass through it in streams and to permit air to be passed through said streams; an air heater connected with said part for heating the air supplied to it; a section below same containing a multiplicity of internally heated vessels over the external surfaces of which the material from the upper part flows or passes in its descent through the apparatus or machine, and air inlet and outlet openings in the walls of the part adapted to permit the passage of air through same and the material. 105

2. In apparatus for drying or conditioning grain or similar substances, the combination of an air contact heating section comprising a plurality of conduits adapted to conduct the material in streams, having apertures in same for the passage of air through said streams; a surface heating section, comprising a multiplicity of internally heated devices over which the material passes; an air moving apparatus connected with the air contact heating part, and with the surface heating part, adapted to force air through the streams of material in the conduits in the upper part, and also through the streams passing over the surface heating part below. 115

3. In apparatus for drying or conditioning grain or similar granular substances, a heater, an upper part of the apparatus having conduits through which the material passes in streams, connected with said heater; and a water heating apparatus, both air and water heaters being heated artificially.
4. Apparatus for drying and conditioning grain or granular substances, comprising an air contact heating section having conduits through which the material passes, and a section below, having a multiplicity of internally heated devices over which the streams of material pass, wherein grain or material controlling or directing means are provided at points over the adjacent edges of adjacent sets of internally heated devices, and adapted to divert or direct the material from the spaces between the edges of said devices to parts of such devices within the edges.
5. Apparatus for drying and conditioning grain or granular substances, comprising an air contact heating section having conduits through which the material passes, and a section below having a multiplicity of internally heated devices over which the streams of material pass, wherein grain or material deflecting and directing devices are employed over the edges of the upper tier of said devices at the planes where the spaces between the different sets come; and means between the adjacent edges of the sets of devices of the lower tier, so as to cause the grain or the like to come under a uniform heating effect by the heating devices; substantially as described.
6. In apparatus for drying or conditioning grain or similar granular substance, comprising in combination a section form-
- ing the uppermost part of the apparatus and to which the cold and moist grain is first introduced, having conduits through which the grain is passed adapted to permit hot air to be passed through the grain or the like in its fall or flow, a metal surface heating section intermediately below the hot air treating section, comprising internally heated devices over which the streams of grain or material pass, and an air heating apparatus external to and connected with the uppermost section and adapted to heat the air to the required temperature supplied to same.
7. In apparatus for drying or conditioning grain or similar granular substances comprising in combination an air heating section having conduits through which the grain is passed adapted to permit air to be passed through the grain or the like in its fall or flow; a surface heating section below the air heating or drying section comprising internally heated devices over which the stream of grain or material pass, and an air heating apparatus external to and connected with the upper air heating section and adapted to heat the air to the required temperature supplied to same, and a water heater external to the sections having the internally heated devices, and connected with different parts of same, the water being adapted to pass or circulate through the water heater and the said sections having the internally heated devices.

In testimony whereof I have signed my name to this specification in the presence of two subscribing witnesses.

WILFRID NIELD ROBINSON.
